UNITED STATES PATENT OFFICE.

JOSEPH GRECO, OF NEW YORK, N. Y.

DESIGN FOR A STOCKING.

Application filed May 7, 1926. Serial No. 17,599. Term of patent 7 years.

To all whom it may concern:

Be it known that I, JOSEPH GRECO, a citizen of the United States, and residing in New York city, borough of Manhattan, in the county and State of New York, have invented a certain new, original, and ornamental Design for Stockings, of which the following is a specification, reference being had to the accompanying drawings, forming a part thereof, and of which—

The lining of the heel portion of the stocking is intended to represent contrasting colors and weave.

I claim:

The ornamental design for a stocking as shown and described.

JOSEPH GRECO.
